JAMES A. CROMBIE, OF BROOKLYN, AND THOMAS S. HOMANS, OF HEMPSTEAD, NEW YORK.

FONT-DISTINGUISHER FOR TYPOGRAPHICAL MACHINES.

1,192,754.

Specification of Letters Patent. Patented July 25, 1916.

Application filed January 6, 1914. Serial No. 810,673.

To all whom it may concern:

Be it known that we, JAMES A. CROMBIE and THOMAS S. HOMANS, citizens of the United States, residing at Brooklyn and 5 Hempstead, in the counties of Kings and Nassau, respectively, and State of New York, have invented new and useful Improvements in Font-Distinguishers for 10 Typographical Machines, of which the following is a specification.

The present invention relates to improvements in typographical machines and more especially to those of the linotype class employing distributing mechanism whereby the 15 matrices after use are returned to the respective magazine channels, and the primary objects of the invention are to provide means whereby matrices belonging to a wrong font are prevented from entering the 20 distributing mechanism or the distributor box forming part thereof and thereby enabling the operator to remove a wrong font matrix with greater facility than heretofore, and to provide means whereby the font 25 distributor can be adjusted readily for different fonts from the front of the machine.

To these and other ends, the invention consists in certain improvements, and combinations and arrangements of parts, all as 30 will be hereinafter more fully described, the novel features being pointed out particularly in the claims at the end of the specification.

35 In the accompanying drawings: Figure 1 is an elevation of a machine of the linotype class as viewed from the left side embodying the present invention; Fig. 2 is a rear elevation of a portion of the distributing mechanism, the same being on an enlarged scale; Fig. 3 represents a section on the line 3-3 of Fig. 2.

Similar parts are designated by the same reference characters in the several views.

45 The present invention is applicable generally to line composing and type casting machines wherein the matrices after a cast has been made therefrom are distributed and returned to the appropriate channels of 50 the magazine. The invention is especially applicable to machines of the linotype class as disclosed generally in the patent to Mergenthaler, No. 436,532. In machines of the class stated, the line of matrices after being

used is carried to the upper rear part of the 55 machine, thence fed through what is known as a "distributer box", the matrices being distributed and returned to the magazine after passing through the distributer box. Heretofore it has been customary to place a 60 device known as a "font distinguisher" at or adjacent to the inner end of the distributer box for the purpose of preventing matrices not belonging to the particular 65 font or set in use from passing to the distributing mechanism. A font distinguisher of such type is disclosed in the patent to Albrecht, No. 560,459. When a wrong font matrix reaches the font distinguisher the 70 distributing operation is interrupted and it is necessary to remove such matrix before the distributing operation can be resumed. Heretofore where the font distinguisher has been placed at or adjacent to the inner end 75 of the distributer box, a wrong font matrix would not reach the font distinguisher until the line of matrices had passed into the distributer box, and the operation of removing the wrong font matrix has proven to be 80 awkward and inconvenient and required the insertion of a rod or special tool. According to the present invention, the font distinguisher is located at the entrance to the distributer box, thereby preventing the entrance of a wrong font matrix into the box 85 and enabling the operator to easily handle the line with the fingers to remove the obstructing matrix.

In the present instance 1 designates part 90 of the main frame of the machine, it having a bracket 2 fixed thereto, and a pair of side plates 3 and 4 secured to the bracket to form the distributer box. A ribbed rail 5 is located within the distributer box and is secured to the under side of the bracket 2, the 95 ribs on this rail coöperating with the teeth in the upper ends of the matrices. The line of matrices passing into the distributer box comes against a stop or shoulder 6 formed on a rail 7, and the matrices are successively removed from the line and engaged with the distributer screws 8 by a lifter 9, the latter being driven in the usual way from a cam 10 on one of the distributer screws. The line of matrices is pushed through the distributer box by a shifter which embodies a head 11 which is carried by an arm 12, the latter being connected to a slide 13 and the

slide reciprocates in a guide 14, the latter being fixed to or forming part of the main frame.

The font distinguisher according to the present invention is mounted at the entrance end of the distributor box, it comprising in the construction shown a rod 15 which is movable longitudinally in a guide 16 and in a direction transversely of the matrix passageway in the distributor box. The rod 15 is formed at its inner end with an upturned tooth 17 which is adapted to occupy a position in line with the font distinguishing notch M' formed in the bottom of each matrix M, it being understood that the font distinguishing notches for all the matrices belonging to the same font or set are located in the same position while matrices belonging to different fonts or sets will have the font distinguishing notches arranged at different positions in a transverse direction. The font distinguisher is movable transversely of the matrix passageway in the distributor box in order that it may be set for the distribution of matrices of different fonts. It follows that if the line contains any matrices, the font distinguishing notches of which are out of line with the tooth 17, the movement of the line into the distributor box will be arrested owing to the engagement of the tooth 17 with an unnotched portion of the odd or wrong font matrix. By arresting the line under such circumstances before the same has reached the distributor box, the operation of removing the odd or wrong font matrix is greatly facilitated, as the line is exposed exteriorly of the distributor box and can be manipulated easily by the hands of the operator. In using font distinguishes of the customary type which extended entirely across the distributor box, it was impossible to place the font distinguisher at the entrance or receiving end of the distributor box owing to the fact that the passage of the arm 12 would then be obstructed. It has been found that the space from the center to the rear or character side of the matrix is sufficient to accommodate the font distinguishing notches and, according to the present invention, the font distinguisher and its supporting guide extend only part-way across the distributor box, a space being provided between the font distinguisher and its guide and the opposite side of the distributor box through which the arm 12 may pass without obstruction.

The present invention also provides means whereby the font distinguisher can be set with the greatest facility by the operator, that is to say, it can be set from the front of the machine and without requiring the operator to go to the back of the machine for this purpose as heretofore. In the construction shown, a link 18 is pivotally connected at 19 to a fork on the outer end of

the rod 15, this link being pivotally connected at 20 to the upper end of a lever 21. This lever 21 is pivoted to a stationary part of the machine at 22 and has a rod or handle 23 pivotally connected to its lower end. This rod or handle extends to the front of the machine within convenient reach of the operator and means is provided for retaining the font distinguisher in different set positions. In the construction shown, a bracket 24 is fixed to the machine and has a slot 25 and a series of teeth or notches 26 formed therein, the rod or handle 23 having a pin or projection 27 which is adapted to travel in the slot 25 and to rest in any one of the notches 26 according to the particular font for which the distinguisher is set. The lever 21 is so proportioned that the notches 26 in the bracket 24 may be spaced apart a considerable distance and correspond with relatively close adjustments of the font distinguisher with the advantage that the operator can readily set the font distinguisher from his seat at the keyboard and the parts can be made more easily as any slight errors in the spacing of the notches 26 would not interfere with the correct operation of the font distinguisher.

We claim as our invention:—

1. In a machine of the linotype class, in combination with the distributor box through which the lines of matrices are passed prior to distribution, of means at the entrance end of the distributor box to prevent wrong font matrices from passing into said box.

2. In a machine of the linotype class, the combination of the distributor box having a channel or raceway through which the matrices are pushed, said channel being open at the lower side, a font distinguisher located at the entrance of said box to prevent the entrance of wrong font matrices and extending part way across the open side of the box, and a matrix pusher having a supporting arm adapted to pass between the font distinguisher and the opposite side of the channel.

3. In a machine of the linotype class, the combination with a distributor box having a passageway for a line of matrices, and means for pushing a line of matrices through said box, of a font distinguisher located at the entrance of said box to prevent wrong font matrices passing into the box and permitting movement of the line-pushing means past the same.

4. In a machine of the linotype class, the combination with a distributor box having a passageway for a line of matrices, said passageway being open at the bottom of the box, a pusher for feeding a line of matrices through said passageway, said pusher having an actuating arm extending upwardly through the open bottom of the box, and a font distinguisher located at the entrance of

the box and extending partially across said passageway from one side of the box and providing a space between it and the opposite side of the box for the passage of the 5 actuating arm of the pusher.

5. In a machine of the linotype class, the combination with a distributer box having a passageway for a line of matrices, a pusher for feeding a line of matrices through said 10 box, and a font distinguisher adjustable to different positions from one side to the center of the said passageway, and an actuating

ing arm for the pusher movable past said font distinguisher in a space between the latter and the opposite side of said passageway. 15

In testimony whereof we have hereunto set our hands in presence of two subscribing witnesses.
